ELLA ROBERSON, OF TULIA, TEXAS.

CHUTE FOR GARBAGE.

1,253,099.

Specification of Letters Patent.

Patented Jan. 8, 1918.

Application filed June 5, 1917. Serial No. 172,973.

To all whom it may concern:

Be it known that I, ELLA ROBERSON, a citizen of the United States, residing at Tulia, in the county of Swisher and State 5 of Texas, have invented new and useful Improvements in Chutes for Garbage, of which the following is a specification.

This invention relates to conveyers, and more especially to chutes; and the object of 10 the same is to produce an outdoor structure or bin which is erected as a lean-to behind the kitchen of the country house, or in fact the kitchen of almost any house, and capable of storing and receiving several of the 15 most needed articles in daily life, and having means for delivering them to or receiving them from the housewife whenever the occasion arises, as well as means for replenishing certain of the articles from the exterior and withdrawing others from time to time.

The invention consists in the general structure and arrangement of parts, and particularly of those parts which relate to 25 the disposition of the garbage, a matter which is ever a vital subject for consideration by the housewife. The invention also provides bins for an ample supply of coal and wood, on which she can draw when these 30 articles are needed; and due consideration is given to the man of the house who must fill the bins from the exterior and take away the garbage pan for the incineration or disposal of its contents.

35 Details will be found in the following specification, reference being had to the accompanying drawings wherein:

Figure 1 is a plan view of this structure complete excepting that its cover is removed, 40 and this view shows in outline a portion of the kitchen and illustrates the position of the stove.

Fig. 2 is a vertical section through the bin on the line 2—2 of Fig. 1, showing the 45 kindling drawer as partly withdrawn.

Fig. 3 is a vertical section on the line 3—3 of Fig. 1, showing the garbage drawer as partly withdrawn.

Fig. 4 is a sectional detail on the line 4—4 50 of Fig. 3, showing the guides for the garbage drawer.

Let us designate the kitchen by the letter K, and the stove S as located near its rear wall W. Outside said rear wall I construct 55 an ample bin 1 having compartments 4 and 5 which are created by an upright partition

6 built transversely across the bin. The top 2 of the bin is closed except for an opening covered with a door 3 above the coal compartment 4. The door in Fig. 2 is shown 60 open, and the top 2 in Fig. 3 closes the garbage compartment so tight as to prevent the entrance of insects and the escape of odors from the garbage, but this compartment may have a tall vent pipe as illustrated. As 65 shown in Fig. 1 there may be an end door 9 in the bin which should also close tightly and preferably be fastened in some manner. The top of the bin preferably slopes away from the kitchen wall W and may be 70 shingled or otherwise rendered water-proof, and the doors will be covered with water-proofing. The materials and proportions of parts are not essential, but if the rear kitchen wall have windows the highest part of the 75 top of the bin should not cover them. The structure is in effect a lean-to, and doubtless will commonly be built of wood.

The compartment 4 is for coal, and its floor 14 leads flush to an outlet opening 15 80 cut through the wall W at the floor line at one side of the stove, and this opening will be closed by a door 16 having a button or other fastening device. Obviously when the housewife opens this door she can secure coal 85 for the stove, and when coal is not desired the door is closed and fastened and all is kept clean. Above the door opening is another numbered 18 from whose lower side guides or cleats 19 extend back throughout 90 the bin to its rear wall, and on these guides slides a drawer 20 which is for wood, either of full size or kindling wood. The front 21 of this drawer is larger than the opening 18 which it overlies and closes tightly when 95 the drawer is in place, and said front may have a handle 22. The drawer is filled with wood or kindlings by opening the cover of this compartment, and through this opening, if it is of sufficient size, coal can be put 100 into the bin. Obviously when the housewife draws out the drawer, wood or kindlings are ready at hand for use in the stove, and at other times the drawer is pushed closed so that its front 21 seals the openings 18 and all 105 is clean.

At the other side of the stove S an opening 30 is formed through the wall W, and from this opening cleats or guides 31 of L-shaped cross section extend back to the rear 110 wall of the bin in parallelism with each other. On these guides slides a drawer 32

whose bottom 33 slopes from its front end to its rear and is provided at its rear end with an opening 34 disposed between the guides. This drawer in effect constitutes a chute, for 5 whatever is put into its front end will run back on its bottom and drop out the opening. The front of the drawer is closed by a plate 36 larger than the opening 30 and has a handle 37 simulating the front plate and handle 10 of the kindling drawer. Beneath the opening 30 is a table or bracket 38 on which the drawer rests when it is partly drawn out; and at the rear end of the drawer is a depending lip 39 of T-shaped structure as best 15 seen in Fig. 4, the head of the T traveling beneath the inner flanges of the guides as the drawer is moved out and in so as to prevent the inner end of the drawer from rising under the weight of the outer end when 20 the drawer is drawn outward too far. This drawer or chute is for garbage or slop, usually poured into its front end in liquid form, and which therefore runs down the inclined bottom and out the hole at the rear end of 25 the same. In the bottom of this compartment 5 beneath the guides is a slop can or pan 40 of considerable length, so that whatever the position of the drawer the opening in its rear end is always over this pan; and 30 therefore if the slops poured into it are sufficiently liquid to immediately run to the rear, they will fall into the front portion of the pan, whereas if the slops are rather thick they will run more slowly and not drop 35 through the hole into the pan until the drawer has been closed. The careful housewife will keep this drawer closed so as to seal the opening 30 and prevent the passage of insects or odors therethrough. The arrangement of other devices and furniture of 40 the kitchen may be such as is most convenient, but the proximity of fuel supply and garbage disposal means to the stove is essential. 45 From the above description it will be seen that the coal in the bin flows through the opening 15 when the door thereof is opened; the wood and kindlings drawer may not act so much in the nature of a chute, but it is of 50 undoubtedly use; and the garbage drawer in any position acts also as a chute because of the rearward incline of its bottom. From time to time the man of the house will remove the garbage pan and empty it, washing it carefully and replacing it and closing and fastening the door 9; and from time to time the housewife will scald the interior of the garbage drawer so that all will 55

be kept clean. On occasions the bin must be filled with coal, and perhaps once a week the 60 drawer must be filled with wood and kindlings. All chutes or drawers are exterior to the building, and preferably just outside the rear wall W of the kitchen K, and therefore the structure takes up no room inside 65 the house, produces no more space which need be heated and cleaned further than as already described, keeps the fuel and garbage under cover, and is a great convenience to the housewife. The proportions and 70 materials of parts are not essential.

What is claimed as new is:—

1. In a chute for garbage and the like, the combination with a lean-to structure built outside a wall and itself having a door 75 opening and means for closing the same, said wall having an opening into said structure, and L-shaped guides disposed within said structure in rear of said opening; of a garbage pan removably mounted beneath 80 said guides, a garbage drawer slidably mounted on the guides and having its bottom inclined to its rear end and there provided with an opening, and a front plate and handle on said drawer, all for the purpose set forth.

2. In a chute for garbage and the like, the combination with a lean-to structure built outside a wall and itself having a door opening and means for closing the same, said 90 wall having an opening into said structure, and L-shaped guides disposed within said structure and standing in rear of said opening; of a garbage receptacle beneath said guides, a rearwardly-inclined chute slidably 95 mounted upon the guides and extending through said opening, a plate closing its front end and having a handle, and a table upon which this chute may be drawn out.

3. In a chute for garbage and the like, the combination with a lean-to structure built outside a wall and itself having a door opening and means for closing the same, said wall having an opening into said structure, and guides disposed within said structure in rear of said opening; of a garbage receptacle beneath said guides, a garbage drawer slidably mounted on the guides and having an opening in its bottom overlying 105 said receptacle, and an inverted T-shaped lip depending from the bottom in rear of said opening, the head of the T engaging beneath said guides, for the purpose set forth.

In testimony whereof I affix my signature.

ELLA ROBERSON.
